ARTHUR M. ACHESON, OF DOBBS FERRY, AND GEORGE RAMSEY, OF BROOKLYN, NEW YORK, ASSIGNORS TO DURIUM PRODUCTS CORPORATION, OF NEW YORK, N. Y., A CORPORATION OF DELAWARE

PHONOGRAPH RECORD

Application filed July 24, 1930. Serial No. 470,385.

The present invention relates broadly to phonograph records and more especially to a record table pin opening structure therefor. The present invention has to do primarily with flexible phonograph records and more especially a phonograph record having a body of paper of substantially card board thickness or some flexible material. Flexible phonograph records having a thin paper body 10 coated with a hard tone groove surface coating may have a tendency to warp which, if it be concave toward the face side of the record, may interfere slightly with the playing of the record. To overcome this difficulty 15 such records may be manufactured in such manner as to be convex relative to the tone groove face side thereof so that when the record is forced down over the record pin on a phonograph table the friction of the record 20 on the pin flattens the convexity of the record and holds the same flat on the record table of the phonograph. Where the sides of the opening in the body of the paper are relied upon to provide friction with the pin, the 25 use of the record tends to enlarge the opening and a condition may arise wherein the opening is enlarged to such a point that friction no longer can be relied upon to hold the record in place. The present invention overcomes the difficulties of the known art by providing an elastic zone around the pin opening so that friction with the pin is maintained without substantial wear on the sides of the opening when 30 the record is placed upon and taken off from the pin. The preferred form of the invention comprises providing resilient rubber member securely located in place in the center of the record with the pin opening being provided in the rubber member. Since the records are relatively thin, it is desirable to support the rubber center in place by supporting means which may comprise suitable thin clamping members of metal or other relatively stiff material. Other features and objects of the present invention will in part be obvious and will in part be pointed out in the specification hereinafter following in which the preferred 50 forms of the invention are disclosed. It is

to be understood that the disclosure herewith is illustrative and not in the limiting sense.

Fig. 1 is a view showing the face of a record slightly in perspective.

Fig. 2 is an enlarged plan view of the central portion of a record. 55

Fig. 3 is a sectional view on line 3—3 of Fig. 2.

Fig. 4 illustrates a slightly modified construction. 60

Fig. 5 is a sectional view on line 5—5 of Fig. 4. 65

Fig. 6 illustrates a further modification of the invention.

Fig. 7 is a sectional view on line 7—7 of Fig. 6. 70

Referring now more especially to Figs. 1, 2 and 3, which illustrate a phonograph record 1 having a paper base with a surface coating 2 carrying the record grooves 4, this record is slightly convex on the face side, as illustrated in Fig. 1 and is intended to be sufficiently flexible to lie flat on a phonograph table when properly placed thereon.

The center member 5 is preferably formed of elastic resilient rubber with sufficient stability to slightly resist compression. This center member 5 is located in an opening formed in the record 1 and is held in place by a top ring 6 which may be formed of sheet metal, such as brass. This top ring 6 is provided with lugs 7 which pass through the record body and are clinched on the back of the record to enclose and support a bottom ring 8. Preferably the rings 6 and 8 slightly compress the edges of the rubber center member and thereby tightly clamp the rubber member in position in the center of the phonograph disc. This rubber member is provided with a pin opening 9 adapted to receive the center pin of a phonograph record table, as is well known in the art. Preferably the pin opening 9 is slightly smaller than the standard size record table pin so that there is a slight compression of the center member when the record is forced in place over the pin. In order to further facilitate the functioning of the elastic center member 5, the rubber member may be provided with slits or slots 10. 100

Figs. 4 and 5 illustrate a slight modification of the device, which modification relates more especially to the holding members, and in Figs. 4 and 5, the center elastic member 5 is held in place by annular ring-like members comprising a top ring 11 and a bottom ring 12. The top ring is formed with lugs 14 cut from material of the top ring and leaving openings 15 in the top ring. These lugs 14 pass through openings in the bottom ring 12 and preferably are so located as to pass through the enlarged openings in the record in which the center member 5 is located. The lugs 14 are suitably bent over the bottom ring 12 to clamp both the body of the record and the center member 5 tightly between the top and bottom rings, thereby securely anchoring the center rubber member in the record. In this form the center member is shown as 20 continuous, namely, it is not slotted or slotted.

Figs. 5 and 6 illustrate a further modification of the present invention in which a rubber center member 20 is located in an opening in the center of the record and this rubber member comprises top edges 21 and bottom edges 22 which extend over the body of the record. These edges 21 and 22 may be relied upon to hold the center 5 in place, although where desired these edges may be securely attached to the record body by cement or other attaching medium. The center of this member 20 is provided with a record table pin opening 24 adapted to receive the pin from a record table. In this form of device, as illustrated in Figs. 6 and 7, the securing edges which attach the central elastic portion to the record body are a part of the center member itself and cooperate with 40 the record body to prevent displacement of the parts during normal rise of the record.

In all the forms of the present invention the pin opening is provided with an elastic member which yields when the record is placed over the record table pin and which is sufficiently rigid to withstand any tendency of the record to slip upwardly on the pin. At the same time the elasticity of the central member militates against wear and grips the center pin so as to assist in causing the rotation of the record with the table to properly rotate the phonograph record when the table rotates.

Having described our invention, we claim:

1. In a flexible phonograph record a body portion, and a resilient center member of material different from the body portion and located at the center of said body portion and being provided with a record table pin opening therein.

2. In a flexible phonograph record, a body portion, a resilient rubber center member located at the center of said body portion and provided with a pin opening, and anchoring

means to anchor said rubber center to said body portion.

3. In a flexible phonograph record, a body portion, a resilient rubber center member located at the center of said body portion and provided with a pin opening, and anchoring means comprising edges extending from said rubber center over a portion of said body portion to anchor said rubber center to said body portion. 75

4. In a phonograph record, a body portion having an opening in the center thereof, a rubber center located in said opening, and means extending over a portion of said body portion adjacent to said opening therein to secure said rubber center in said opening, said rubber center having a pin opening adapted to frictionally engage a center pin on a record table of a phonograph. 80

5. In a flexible phonograph record a body portion having an opening in the center thereof, and a resilient rubber center located within said opening in the body portion, said rubber center having a pin opening therein, and rigid means to retain said rubber center 85 in the opening in the body portion. 90

6. In a flexible phonograph record a body portion, a resilient rubber center located at the center of said body portion and having a pin opening therein, and a clamping ring 95 securing said rubber center to said body portion.

7. In a flexible phonograph record a body portion having an opening in the center thereof, a rubber center mounted in said opening and having a pin opening, a pair of clamping rings engaging said body portion and said rubber center, and means to clamp said rings tightly against said body portion and said rubber center. 100 105

8. In a flexible phonograph record a body portion having an opening in the center thereof, a rubber center mounted in said opening and having a pin opening, a pair of clamping rings engaging said body portion and said rubber center, and lugs passing through said body portion to clamp said rings tightly against said body portion and said rubber center. 110

9. In a phonograph record a flexible body portion provided with an opening in the center thereof, said flexible body portion being bowed to comprise a convex face, a rubber center secured at the center of said body portion and being provided with a pin opening 115 to engage the pin of a phonograph record table. 120
